UNITED STATES PATENT OFFICE.

BENJAMIN A. MITCHELL, OF NEW YORK, N. Y.

CRUSHER.

Application filed May 24, 1923. Serial No. 641,040.

To all whom it may concern:

Be it known that I, BENJAMIN A. MITCHELL, a citizen of the United States, residing in the borough of Richmond, of the 5 city of New York, in the State of New York, have invented certain new and useful Improvements in Crushers, of which the following is a specification, reference being had to the accompanying drawing, forming a 10 part hereof.

In a co-pending application for Letters Patent of the United States, Serial No. 520,794, filed December 8, 1921, there is shown and described and covered broadly a 15 crusher in which the relatively movable crusher member is actuated by the centrifugal force developed by a freely movable intermediate body having a mass center eccentric to the axis of rotation of an impeller 20 which forms a part of a rotating system. In the construction shown and described in said application as an embodiment of the invention covered thereby, the impeller rotates upon a fixed axis, with reference to 25 which the movable crusher member, actuated by the centrifugal force developed by the freely movable, intermediate body, has a movement of gyration. The operation of a crusher so constructed is satisfactory if the 30 dimensions of the moving parts of the crusher are not too great and in operation upon some classes of material. It is found, however, that in operation on other classes of material and with a diameter of the relatively 35 movable member of the crusher and mass of the intermediate body as great as might otherwise be desirable for practical purposes, there sometimes results, as from the entrance between the two members of 40 the crusher of a relatively large piece of relatively hard material, a slowing down of the crusher with the consequent loss of efficiency, and a somewhat destructive action of the intermediate body on the impeller. 45 This is due to the fact that the displacement of the relatively movable member of the crusher by such relatively large and hard piece, permits the intermediate body to have, under the influence of centrifugal action at 50 a point diametrically opposite that at which such relatively large and hard piece is introduced, an increased radius of movement. The intermediate body therefore has a maximum linear velocity at the point toward 55 which the relatively movable member of the

crusher is displaced and a minimum linear velocity at the point from which the relatively movable crusher member is displaced. There is therefore, during one half of the revolution of the intermediate body an acceleration of linear velocity of such body and during the other half a retardation of such body. From this action there results a relative movement as between the impeller and the intermediate body which brings about a peening action of the intermediate body upon the impeller and a slowing down of the impeller. The peening action, at the high rate of rotation of the impeller which it is desirable to attain, is somewhat destructive and, since the efficiency of the crusher depends upon centrifugal action and therefore upon velocity, the slowing down of the impeller reduces the efficiency of the crusher. It is the object of this invention to overcome these objections and to accomplish this result the construction of the crusher described in said application is so modified that, while the principle of operation remains the same, the radial distance of the intermediate body from the axis of the impeller is uniform at all times and under all conditions of operation. The speed of rotation of the impeller being constant, the linear velocity of the intermediate body is constant and the undesirable action above described cannot take place. As a means to maintain the constant radial distance of the intermediate body from the axis of the impeller, the shaft of the impeller is made to partake of the gyroscopic movement of the movable member of the crusher upon which the intermediate body acts, the axis of the impeller coinciding at all times with the axis of such relatively movable member of the crusher. As a matter of practical construction, the shaft of the impeller is mounted in bearings which are supported by the gyroscopic member of the crusher and is suspended so that it is free to gyrate about the same point as the gyroscopic member of the crusher. The invention will be explained more fully hereinafter with reference to the accompanying drawing in which—

Figure 1 is a view in sectional elevation of a crusher which embodies the present invention, and

Figure 2 is a partial view in horizontal section of the plane indicated by the broken line 2—2 of Figure 1.

The relatively fixed crusher member 15, having a lining 21, is surmounted by a frame 16 which supports, through an internally threaded ring 33, so as to provide for vertical adjustment, a casing or housing 28 in which may be disposed a motor 43. A tubular shaft 40 of the rotor 44 is mounted in a sleeve bearing 41, in the tubular extension 17 of the housing 28, and in a composite radial and thrust bearing 42 at the upper end of the housing. At the lower end of the extension 17 there is formed a spherical enlargement 18 upon which is suspended, so as to be capable of gyratory movement, the relatively movable member 20 of the crusher, which carries the tapered mantle 25 to form, with the lining 21, a space with converging walls between which the crushing of the material is carried on progressively in the operation of the crusher. The spherical enlargement 18 is received in the construction shown in a spherical seat formed in two rings 18^a and 18^b which are seated in the sleeve-like extension of the crusher member 20 and are held in place by a sleeve nut 18^c. Within the mantle 25 are supported the raceways 48 with which contact, under the influence of centrifugal action, the balls or intermediate members 46, the latter being received in recesses 47 of the balanced impeller 45.

The parts thus far referred to and described herein merely as a structure adapted for the application of the present invention, are constructed and arranged substantially as described in said application and for convenience are identified, as far as possible, by the same reference numerals as those employed in said application, with particular reference to the embodiment of the invention as shown in Figures 2 and 3 of the drawings of said application.

In the several embodiments of the invention described in said application, the impeller rotates upon an axis which is fixed with respect to the stationary member of the crusher and the movable member of the crusher gyrates about such fixed axis, with the result, as already explained, that the radial distance of the balls or intermediate members 46 from the axis of the impeller, may vary and, as a consequence, that the linear velocity of such balls or intermediate members may vary during each revolution of the balls about the axis of the impeller. In accordance with the present invention, however, provision is made whereby the radial distance of the balls from the axis of the impeller shall be constant and the linear velocity of the balls shall also be constant if, as is presumed, the speed of rotation of the impeller is constant. To this end, the impeller is so supported as to be concentric at all times with the movable member 20 of the crusher and therefore to gyrate with the

crusher about the center of the spherical support 18 of the movable crusher member 20. In the construction shown, the shaft 40 of the motor 43 is supported in fixed bearings in the housing 28 of the tubular shaft 45^a of the impeller 45, forming an extension of the shaft 40, and is coupled thereto through a loose joint 45^b, of ordinary construction, which permits the shaft 45^a to gyrate with respect to the axis of the shaft 40. This shaft 45^a is mounted in a composite radial and thrust bearing 45^c, placed in the head of the movable crusher member 20, and in a sleeve bearing 45^d placed in the plate 22 which supports the mantle 25 and is held to the head of the member 20 by bolts 24, as described in said application.

It will be understood that the mounting of the shaft of the impeller in bearings which are carried by the movable member of the crusher and in concentricity therewith, constitutes a convenient means by which the radial distance of the balls or intermediate members from the axis of the impeller is constant under all conditions of operation and that, therefore, the linear velocity of the balls or intermediate members will be constant, if the speed of rotation of the impeller is constant, and the disadvantages due to variation in linear velocity will be overcome. It will be obvious that various changes in details of construction will be made to suit different conditions of use, as in the several embodiments of the main invention shown in said application, and that the present invention, except as indicated in the claims, is not limited to any particular construction.

I claim as my invention:

1. In a crusher, the combination of a relatively fixed crusher member, a relatively movable crusher member, a balanced impeller, a freely movable intermediate body interposed between the impeller and the relatively movable crusher member and subject to the action of centrifugal force, and means to maintain the radial distance of such intermediate body from the axis of the impeller constant throughout the revolution of the intermediate body.

2. In a crusher, the combination of a relatively fixed crusher member, a relatively movable crusher member, a balanced impeller, a freely movable intermediate body interposed between the impeller and the relatively movable crusher member and subject to the action of centrifugal force, and means to maintain the impeller in concentricity with the relatively movable crusher member.

3. In a crusher, the combination of a relatively fixed crusher member, a gyratory crusher member, a balanced impeller, a driving shaft for the impeller, supported for gyration with the gyratory crusher member, and a freely movable intermediate body in-

terposed between the impeller and the gyratory member and subject to the action of centrifugal force.

4. In a crusher, the combination of a fixed crusher member, a supporting frame thereon, a motor and shaft supported in fixed bearings in the frame, a gyratory crusher member suspended from the frame, an impeller, an impeller shaft mounted in bearings in the gyratory crusher member and loosely jointed with the motor shaft, and a freely movable intermediate body interposed between the impeller and the gyratory member and subject to the action of centrifugal force.

5. In a crushing apparatus, a crusher casting forming a crushing chamber, a weighted body rotatable on its own axis and free to shift its axis under centrifugal force developed during rotation, a flexible driving connection for rotating said body, and a crusher head having a universal suspension and actuated by the direct contact of said weighted body.

6. In a crushing apparatus, a crusher casting forming a crushing chamber, a weighted body rotatable on its own axis and free to shift its axis under centrifugal force developed during rotation, a flexible driving connection for rotating said body, and a crusher head having a universal suspension and actuated by the direct contact of said weighted body, the crusher head having an interior diameter substantially larger than the diameter of the weighted body.

7. In a crushing apparatus, a crusher casting forming a crushing chamber, a crusher head having a universal suspension, a pendulum within the crusher head, and a flexible driving connection for rotating said pendulum on its own axis, whereby the crusher head is actuated by the movement of the pendulum under the centrifugal force developed upon rotation of the latter.

8. In a crushing apparatus, a crusher casting forming a crushing chamber, a crusher head having a universal suspension and provided with an interior race, a pendulum within the crusher head of less diameter than that of the race and having a portion adapted to run on said race, and a flexible driving connection for rotating said pendulum on its own axis, whereby the pendulum is caused to run on said race, to actuate the crusher head.

9. In a crushing apparatus, a crusher casting forming a crushing chamber, a crusher head having a universal suspension and provided with an interior race, a pendulum within the crusher of less diameter than that of the race and having a portion adapted to run on said race, a drive shaft, and a connection including a universal joint, between said drive shaft and the pendulum, for rotating the latter on its own axis, whereby

the pendulum is caused to run on said race, to actuate the crusher head.

10. In a crushing apparatus, a crusher casing forming a crushing chamber, a crusher head having a universal suspension and provided with an interior race, a pendulum within the crusher head of less diameter than that of the race and having a portion adapted to run on said race, a flexible driving connection for rotating said pendulum on its own axis, whereby the pendulum is caused to run on said race, thereby to actuate the crusher head, and means for preventing the pendulum from taking a vertical position.

11. In a crushing apparatus, a crusher casting forming a crushing chamber, a crusher head having a ball and socket suspension and provided with an interior race, a pendulum within the crusher head and having a portion adapted to run on said race, the diameter of said portion being less than the diameter of the race, a drive shaft, and a connection including a universal joint between the drive shaft and the pendulum for rotating the latter on its own axis.

12. A gyratory crusher, comprising in combination, a crusher bowl, a crusher head mounted for gyratory movement within said bowl, and means within the head, positively rotatably about a floating axis and centrifugally moved outwardly to engage the head to impart gyratory movement thereto, said means being yieldable inwardly toward the axis of said bowl against the centrifugal force acting thereon.

13. A gyratory crusher, comprising in combination, a crusher bowl, a crusher head mounted for gyratory movement within said bowl, and rotatable universally supported means within said head, adapted to co-act therewith to impart gyratory movement thereto.

14. A gyratory crusher, comprising in combination, a crusher bowl, a crusher head mounted for gyratory movement within said bowl, and rotatable universally supported means within said head, adapted to co-act therewith to impart gyratory movement thereto, said head and means being yieldable toward the axis of the crusher bowl.

15. A gyratory crusher, comprising in combination, a crusher bowl, a crusher head mounted for gyratory movement within said bowl, and having an interior surface, and a driven element rotatable about its axis within said head, of smaller effective diameter than said interior surface, said means being movable to engage said surface to impart gyratory movement to said head.

16. A gyratory crusher, comprising in combination, a crusher bowl, a crusher head mounted for gyratory movement within said bowl and having an interior surface, and a positively driven gyratory element within

said bowl of smaller effective diameter than said surface, said means co-acting with said surface to impart gyratory movement to said head.

5 17. A gyratory crusher, comprising in combination, a crusher bowl, a crusher head mounted for gyratory movement within said bowl, and a positively rotated centrifugally acting means within said head for effecting

10 gyratory movement thereof.

18. A gyratory crusher, comprising in combination, a crusher bowl, a crusher head mounted for gyratory movement within said bowl, and positively rotated means within

15 said head movable outwardly by centrifugal force into engagement with said head to impart gyratory movement thereto.

19. A gyratory crusher, comprising in combination, a crusher bowl, a crusher head

20 mounted for gyratory movement within said bowl, and means within said head rotatable about its own axis and constrained by centrifugal force to normally move in a path

about the axis of the bowl, and co-acting with said head to impart gyratory movement 25 thereto.

20. A gyratory crusher, comprising in combination, a crusher bowl, a crusher head mounted for gyratory movement within said bowl, and a driven means having a gyratory 30 movement within said head and capable of movement toward and from the axis of the crusher bowl and adapted to engage said head to effect gyratory movement thereof.

21. A gyratory crusher, comprising in combination, a crusher bowl, a crusher head mounted for gyratory movement within said bowl, and a positively rotated means within said head also having a variable or non-fixed orbital movement about the axis of the 40 crusher bowl adapted to engage the crusher head to effect gyratory movement thereof.

This specification signed this 23d day of May, A. D. 1923.

BENJAMIN A. MITCHELL.
